UNITED STATES PATENT OFFICE.

ADELVIN B. LYMAN, OF CLEVELAND, OHIO.

ELECTRIC ANNUNCIATOR.

SPECIFICATION forming part of Letters Patent No. 488,567, dated December 27, 1892.

Application filed October 26, 1891. Serial No. 409,769. (No model.)

To all whom it may concern:

Be it known that I, ADELVIN B. LYMAN, a citizen of the United States, residing at Cleveland, in the county of Cuyahoga and State of Ohio, have invented certain new and useful Improvements in Electric Annunciators, of which the following is a full, clear, and complete description.

The nature of my invention relates to an annunciator so constructed as not to require the resetting of the needle after the bell has rung. The mechanical parts being so arranged that the needle always indicates the location of the caller itself. The annunciator is also small and inexpensive as compared with those in ordinary use.

That the invention may be seen and fully understood by others skilled in the art, reference will be had to the following specification and annexed drawings forming part thereof.

Figure 1. is a front elevation of my improved annunciator, showing the connections. Fig. 2. is a perspective view, in elevation showing the annunciator disconnected, with the cover removed and a portion of the bell broken away for the purpose hereinafter shown. Fig. 3. is a vertical section through the middle of the annunciator as indicated by dotted line *x*. *x*. Fig. 4. is a front view on an enlarged scale of a vibrating hammer and rheotome. Fig. 5. is a diagram of the electrical circuits and connections.

Like letters and numerals of reference designate like parts in the drawings and specification.

Only two pairs of electro magnets *a* and *b* Fig. 2. are used, the mechanical arrangement being such as to cause the said magnets to perform two separate duties at the same time, viz: to ring the bell *c*. by attracting the armature *d*. and causing the bell hammer *e* or *f* as the case may be, to strike the bell *c*. and at the same time attract the pivotal armature *g*. which causes the pin *h*, attached to said armature *g* to come in contact quickly with one of the arms *i* or *i'* Fig. 1. of the pointer *j*. The pointer *j*. is so pivoted at *k*. that a sudden blow of the pin *h*. will throw the pointer head *l* beyond the center of gravity and cause it to point and remain at the name on

dial which corresponds with the location from which the call comes.

The poles of the magnets are extended, by soft iron pieces *m*. *m* being placed on the ends thereof to cause the same magnets that ring the bell, to operate the said armature *g*, these soft pieces *m*. *m*. are placed in such a manner that they extend up above the direct end of the magnet cores which operate the bell armature *d*. thereby allowing the armature *g*. a free and independent movement between the magnets *a*. and *b*. arranged as shown in Fig. 2.

In order to ring the same bell with two different pairs of magnets it is necessary to have a double bell hammer *e*. and *f*. so as to strike the bell on either side separately. It is also necessary to have two distinct circuit breaking, and closing springs on the same armature as shown at *o*. *o'* Fig. 4. The springs *o*. and *o'*. operate in connection with the insulated contact points or screws *p* and *q* Fig. 2. thus causing the vibrating stroke of the hammer on the bell. The springs *o*. *o'* are normally in contact with the screws *p* *q* respectively. When the circuit is closed at a push button through one of the magnets, the armature is attracted, and the spring is drawn away from its screw, thereby breaking the circuit and releasing the armature; whereupon it withdraws from the magnet, and the spring is brought back against the screw, closing the circuit and again causing the armature to be attracted. This action keeps the armature vibrating so long as the circuit is closed through either pair of magnets. The screws *p* and *q* can be so adjusted as to ring the bell with a quick, rapid vibration or with a slow vibration thus enabling a person to distinguish the location of the call by the sound of the bell without reference to the indicator. For instance: If the screw *p*. be so adjusted to cause a slow vibration and a call comes from the front door or side door as the case may be, it is readily distinguished without reference to the dial.

While this is not necessary it is in many cases a great advantage and convenience.

If the pointer *j*. is pointing to "Front Door" on the dial Fig. 1. and the push button *r* or "Front Door" button is pushed, the bell rings and the pointer remains at "Front Door." on dial. But should the button *r'*. or "Side Door."

button be pushed the pointer j , will be thrown over and point to "Side Door" on the dial (as shown by dotted line j' . Fig. 1.) and "vice versa."

5 When it is desired to have a third call, say, "Dining Room," this same apparatus can be connected by a separate battery. The push button r' is connected with the binding post J of the battery A by the wire 1 and with the binding post G by the wire 2, from which the circuit extends through the wires 3 and 4, the electro magnets b b , and the wire 5, to the binding post D , and from the post D , by the wire 6 to the post E , which is connected with the binding post I of the battery A , by the wire 7, thus completing the circuit. When the circuit is closed the magnet becomes energized and attracts the armature d causing the bell hammer to strike the bell just once 20 or what is known as a single stroke bell, thereby distinguishing the dining room call by sound of bell alone.

The push button r' is connected with the binding post K of the battery B , by the wire 8, and with the binding post D by the wire 9, from which the circuit extends through the wire 5, electro magnets b b and the wire 4, to the platinum point of the screw p which makes contact with the spring o . The circuit continues through the screw p and spring o to the post F by way of the wire 10, and the wire 11 connects the post F with the binding post L , of the battery B , thus completing the circuit. The push button r is connected with the binding post K of the battery B by the wires 12 and 8, and with the binding post H by the wire 13, from which the circuit extends through the wire 14, electro magnets a a and the wire 15 to the platinum point of the screw q , which 30 is in connection with the soft iron standard. The circuit continues through the screw q

and spring o' to the post F by way of the wire 10, and the wire 11 connects the post F with the binding post L of the battery B , thus completing the circuit.

What I claim and desire to secure by Letters Patent is.

1. An electric annunciator having a pair of oppositely disposed magnets, a vertical armature free to oscillate between the poles of said magnets and pivoted at its lower end, a pin on said armature, and a pointer pivoted on a support independent of the armature below its center of gravity, and arranged to be actuated by said pin when the armature is oscillated, substantially as described. 45

2. In an electric annunciator, the combination with a pair of oppositely disposed magnets, having laterally extended pole pieces, of a vibrating bell hammer and an oscillating armature arranged vertically between said pole pieces, and pivotally supported at their lower ends, a pin on said armature, and a pointer pivoted on a support independent of the armature below its center of gravity and 60 having a forked end, within which said pin plays to actuate the pointer by sudden contact with the arms of said fork, substantially as described. 65

3. In an electric annunciator, a pair of magnets and push buttons connected in multiple arc, with a vibrating armature common to both magnets and forming a part of each circuit, and an additional battery and push button connected directly with one of said magnets, substantially as described. 70

In testimony whereof I affix my signature in presence of two witnesses.

ADELVIN B. LYMAN.

Witnesses:

W. H. BURRIDGE,
L. F. GRISWOLD.
